UNITED STATES PATENT OFFICE.

MAXIMILIAN WEIL, OF NEW YORK, N. Y., ASSIGNOR, BY MESNE ASSIGNMENTS, TO
AUTOMATIC RAILWAY CONTROL COMPANY, INC., OF NEW YORK, N. Y.

AUTOMATIC TRAIN-CONTROLLING MEANS.

1,304,833.

Specification of Letters Patent. Patented May 27, 1919.

Application filed January 19, 1914. Serial No. 812,944.

To all whom it may concern:

Be it known that I, MAXIMILIAN WEIL, a citizen of the United States, residing at New York, in the county of New York and State of New York, have invented certain new and useful Improvements in Automatic Train-Controlling Means, of which the following is a full, clear, and exact specification.

This invention relates to automatic train controlling means, and has particular reference to a system whereby two trains are permitted to move on the same track while permitting the following train to be automatically controlled as to its speed by the leading train as long as the two trains are within a predetermined danger zone. As soon as the leading train passes out of the danger zone control over the following train the latter train becomes free of the automatic devices until it again comes into a danger zone. The invention is especially applicable in connection with block signaling systems, also wherein what are known as "cut sections" are used, that is where a block is of such length that for convenience in supplying current to the track relays and to avoid excessive drop it is cut into sections each having a track battery or other source of supply. It will be seen that an automatic controlling system permitting the trains to move in such a block under proper conditions is very desirable and advantageous.

A further object of the invention is to provide a closed circuit system which will detect its own failures, and including separate locomotive and track circuits. That is, the normally closed track circuits are not interlocked with the normally closed locomotive circuits, yet a failure in any part of one circuit immediately causes the automatic operation of stopping or controlling devices or signals as may be desired by the constructor. A train equipped with this system is free to go where the track is not equipped with the required automatic controlling circuits, or vice versa, without interference with the normal control exercised by the engineer. This is an important prac-

tical consideration in that operating conditions do not always require the entire equipment of a system with automatic controlling means, so that practicable systems must be made independent of sidings, switches and unequipped sections of track.

A further object of the invention is to enable the automatic controlling means for a signal or brake to operate differently at different places along the track, such for example as at draw-bridges, cross-overs or ordinary signals. In the case of a draw-bridge or a cross-over, a quick and extreme stop might be desirable while not being at an ordinary signal.

Figure 1 is a diagram showing the track circuits of the improved system adapted for ordinary blocks;

Fig. 2 shows the invention applied to cut section track circuits;

Fig. 3 is a detail view showing the winding of a differential coil employed in connection with a tuned reed for producing alternating or periodic currents which act upon the locomotive devices;

Fig. 4 is a diagram of the locomotive circuits, partly in perspective;

Fig. 5 is a wiring diagram showing the windings of the differential magnets carried on the locomotive;

Fig. 6 shows a modified arrangement applicable to Figs. 1 and 2 for providing an increased actuating current for the tuned track relay;

Fig. 7 is a detail of the core winding.

In applying this system, no changes are required in the present standard railroads having track circuits divided into blocks for signaling or other purposes, wherein a normally energized track relay is short-circuited by the wheels of a train upon entering the block. With this invention, when the track signal relay is short-circuited, the magnetization of a differentially wound track relay is so changed as to set a tuned relay device into operation, such as a tuning fork. As herein shown, the differential windings are connected to adjoining blocks, so that the tuned relay device acts in one block.

when there is a train in each. This permits periodic currents to flow in a circuit inductively related to normally ineffective locomotive circuits, thereby causing them to operate upon the brakes or signal devices in a manner varying with the condition of the track ahead and the proximity of other trains. These circuits are normally closed, so as to be self detecting.

In Fig. 1, X represents a block having a train 1 therein and Y an adjoining block having a following train 11 therein. 3 represents an ordinary track relay having the armature 2 and supplied by track battery 8, one pole of which is connected directly to one rail and the other pole to the other rail through contact 9 and one leg of a tuning fork or tuned reed 10. The tuning fork is normally at rest, and is only set in vibration by the presence of trains in adjoining blocks. The entering of train 11 into block Y will drop the armature 2 in the usual manner and also short-circuit the winding 3. Between the legs of tuning fork 10 is a differentially wound magnet comprising a core 5 and coils 6 and 7, shown in detail in Fig. 3. The coils 6 and 7 are connected at their meeting point with a wire leading from armature 2 through a resistance 4, the armature 2 and the resistance 4 constituting a shunt circuit around coil 6. This shunt is closed when track relay 3 is energized, as shown in Fig. 3. The ampere turns of coil 6 and the resistance 4 are so adjusted that the ampere turns in coil 6 will be equal and opposite to those of coil 7 when the shunt is closed. One end of coil 7 is connected to the base of the tuning fork 10 by wire 9 so that coils 6 and 7 will be opened and closed by the vibration of the tuning fork. When the shunt circuit around coil 6 is opened by the dropping of armature 2 the coils 7 and 6 will oppose each other, thereby producing a resultant magnetization by coil 6 (because of its larger number ampere turns) but not sufficient to vibrate the fork. The magnet coil 3 is also in series with coils 6, 7. When there is a train in the block X and the resistance of coil 3 is removed by a train entering block Y, the core 5 becomes more strongly magnetized, and sets the tuning fork 10 into vibration. This causes a periodic current to be applied across the rails in block Y, passing through the axle of train 11.

Considering first the train 1 in block X, without the train 11 in block Y, it will be seen that the relay 3 when short-circuited causes its armature 2 to open the normally closed shunt circuit around coil 6 of differential magnet 5. This has no effect upon the tuning fork 10 because there is no train in block Y and the resistance of track relay

3 is in series with coil 7 on the differential magnet, so that there will not be sufficient unbalance produced to cause the vibration of the tuning fork or reed 10. The relay 3 will still be supplied with continuous current from track battery 8. As soon, however, as a second train 11 enters block Y, it will shunt out the resistance of relay 3 and the magnetic unbalance in differential magnet 5 is at this time sufficient to produce the vibration of the tuning fork or tuned reed, as the case may be. The tuning fork or tuned reed having a certain natural period of vibration will cause the current thus sent into the track rails to be "tuned" as it were, that is, the current will have a fixed frequency or periodicity. This increase of current through differential magnet 5 when train 11 enters block Y may, in some cases, not be sufficient to bring about the desired results and in that case a "double shunt" is placed across coil 6 (see Fig. 3) as is shown in Fig. 6. A train entering block X¹ will cause the fall of armature 2 opening the shunt of differential 3. The shunt, however, will still remain closed through wire 12, armature 13, wire 14, rail 15 and wire 16. As soon, however, as a train enters block Y¹, the armature 13 will drop opening the second shunt and causing the vibration of tuning fork or tuned reed 10.

The track circuits have to be somewhat modified for a cut-section. This is shown in Fig. 2. The distance between O—P constitutes a block which is "cut" at R. Y² is the relaying half, whereas Z² is the relayed half of block O—P. A train entering block X² will, as before, open shunt 4 by causing the fall of armature 17. It will also cause the fall of armatures 18 and 19, which armatures will reverse the polarity of track battery 8 across the rails. This will cause the polarized armature 20 of relay 21 to open shunt 4, whereas the neutral armature 22 will retain its position as shown. The differential magnet 5 of block Z² is now ready to receive a train in block Z² and as soon as the train enters this block the current across the rails in block Z² will become "tuned", as was above explained in connection with Fig. 1. As the train is entering block Y² it will receive its control energy from the track battery 8 of block Y² and it will also cause the fall of neutral armature 22, thus opening-circuiting battery 8 and short-circuiting the track rails in block Z² which will cause the fall of armatures of relay 3 in block Z². The action of which will be the same as the fall of armatures 18, 19 of relay 3 in block X² as was explained. It will be seen that in this way the train control energy is relayed in the same manner as the energy for the present semaphore controlling devices. It will also be seen that the cut section Z² Y²

acts like a single uncut section in conveying control energy to the train. Thus while a train is in either part of the cut section, it is properly protected against a train following.

The ring core 24 is placed around the axle 25, and when an interrupted periodic current is used (as distinguished from an alternating periodic current) the core 24 is preferably provided with an air gap, as shown, to reduce possible objectionable effects of residual magnetism. The ring core is preferably laminated and has a duplex winding composed of wires *a* and *b* wound in parallel. The resonating relay 26 has also a similar winding composed of wires *c* and *d*. The connections of these windings will best be understood by referring to Fig. 5. The winding *a* and the winding *b* of the secondary are here shown separately joined to the copper bar *c* at 27 and 28. The two windings are supplied with continuous current from battery 29 and since the winding *a* and winding *b* constitute a duplex winding, the current from battery 29 will have no magnetizing effect. The winding of the resonating relay 26 is also shown separated and the respective windings *d* and *e* of this relay are joined to the same copper bar *c* at 30 and 31. The resonating relay winding is also supplied with current from battery 29 and, since the windings *d* and *e* are parallel, the magnetic effects of the current supplied from battery 29 will be nullified. It is desirable that the magnetic effects should be *nil* normally in the windings of the resonating relay, as well as in the windings of the ring core 24. Such a condition can be brought about when the current in the winding *d* is equal and opposite to the current in the winding *e*, and the current in winding *a* is equal and opposite to the current in winding *b*. This condition is made to exist by so arranging the windings on the core 24 and the windings on the resonating relay that normally there is no battery current flowing from K to L or from L to K. It will be seen that as long as this condition of electrical equilibrium exists there will also be a magnetic balance in the windings of the resonating relay as well as in the windings of the core 24. The battery current will flow through the circuits as shown by the arrows drawn in the windings. The periodic current flowing through the axle 25 (which axle constitutes the primary of a transformer) will induce an alternating E. M. F. in the windings of core 24, that is in the windings *a* and *b*, these being in parallel, the E. M. F. in these two windings will be equal and parallel. Therefore, there can be no flow of current due to this induced E. M. F. through the battery 29 and the only way this induced E. M. F. can produce a flow

of current will be through the windings of resonating relay 26. If a direction for this alternating current at any instant be assumed it will flow as shown by the dotted arrows. Although the battery current through the resonating relay windings flows in the two windings *d* and *e*, the current due to the induced alternating E. M. F. will at any instant flow in the same direction in both of the windings of resonating relay 26, with the net result that the fluxes due to the battery current nullify each other whereas the fluxes due to the alternating current aid each other. The resonating relay consists of a permanent magnet which is split at 32, providing like poles shown at N and N and a pole S of polarity as shown. The tuned reed 33 is placed between the two like poles and since the poles are normally of the same strength this reed will be undisturbed. As soon as a tuned current is supplied to the resonating relay windings, that is a current having a frequency the same as the natural period of vibration of the reed 33, the reed 33 will be thrown into vibration, open-circuiting the magnet 34 through the contacts 35 and 36. Magnet 34 will remain deenergized, because the reed 33 has a period of vibration greater than that of the vibrating contacts 35, 36, so that there will always be an open circuit between the reed 33, when vibrating, and the contacts 35, 36. As soon as the tuned current is withdrawn from the windings of resonating relay 26, the reed 33 will come to a stop, again closing the circuit of magnet 34. If now a signal of different character is desired to be transmitted to the train at a given location then a tuning fork 10^u or reed having a different frequency (not an even harmonic of the other tuning forks or tuning reeds used along the right of way) from the other tuning forks is placed in the circuit of the track battery 8^x and another reed 37 whose natural period of vibration will correspond to that of the before mentioned tuning fork 10^u is placed in the resonating relay 26. This reed 37 will control the circuit of magnet 38 so that when the train reaches the location where this tuning fork or tuning reed is placed the tuned current sent to the windings of the resonating relay 26 will at this time be such that no other reed in the resonating relay will respond to it but the particular one, that is 37, operating magnet 38 thus giving the desired signal or action on the brakes. As herein shown, the tuning fork vibrator 10^u will be set into vibration when a train reaches block X and the magnet U^x is deenergized by the opening of switch *t* when a track switch C in block U is set so as to run the train onto another track. When switch *t* is opened, the armature 2^z drops, thereby unbalancing

the differentially wound magnet of tuning fork vibrator 10^a, which commences to vibrate when the train enters block X. When the track switch is open and the track in block U is in normal condition, the tuning fork vibrator 10^a exercises control on the train in block X when there is a train in block U. The magnet U^a is held energized by a local battery 8, or in any other desired manner. In this manner any number of tuned reeds may be placed on the resonating relay to respond to tuning forks or tuning reeds of different frequencies along the right of way. An extra reed is shown at 39.

15 The axle 25 is preferably non-magnetic and is made of material, such as manganese steel, to reduce eddy currents to a minimum. If the ordinary steel axle is used the eddy currents produced may render it difficult 20 under unfavorable conditions to obtain sufficient current in the windings of core 24. The axle 25 is further clad with a material having a higher conductivity than the axle itself so that the current will keep on the 25 surface of the axle, thereby forcing the flux produced by this current into the core 24 where it will cut the conductors wound on core 24. The more suitable material for this, of course, would be copper and it would be 30 placed around the axle at 40. Copper bars would also be placed around the wheel, as shown at 41, these copper bars being joined to the sleeve 40 and they are so fixed that they make a very good contact with the 35 wheel so that the current is led off the wheel into the copper bars 41 and then into the sleeve 40. The object of which is, as was explained above, to keep the "tuned" current to the surface of the axle 25.

40 The object of the battery current through the parallel windings of core 24 and resonating relay 26 is to render the locomotive circuits self detecting. That is to say, should any brake take place in any of the 45 locomotive circuits it will be followed by an application of the brakes. This can be seen by reference to Fig. 5. For example, should an open circuit take place in the winding *d* of resonating relay 26 then there would be 50 a battery current flowing through the winding *e* which would produce a magnetic flux. This will cause one of the reeds in the relay to act as the armature of a polarized relay and it will be drawn to one side, open-circuiting the particular circuit which it controls. This will take place no matter what 55 break takes place in any of the circuits for the reeds remain neutral only as long as there is an absolute electrical equilibrium in 60 the current produced by the battery 29. That is to say, as long as there is no current flowing from K to L or from L to K. A further object of the battery current through the windings of core 24 and the resonating relay,

is to render the magnetic circuits more sensitive to changes in magnetic flux, due to the alternating current, the battery current being normally without magnetizing effect.

The magnets 34, 38, etc., will be suitably connected to set air brakes, or other devices, 70 as may be desired.

While the specific embodiment of the invention herein illustrated shows what is known as a two rail system, for the purposes of this invention a single rail system, that is where only one rail is divided into insulated blocks, is an equivalent. Also, where a "periodic" or "tuned" current is referred to herein, I do not restrict myself to an interrupted direct current across the rails, or such an induced secondary current in the locomotive circuits as results therefrom, but intend to cover periodic or alternating currents of any other character and equivalent means for producing them. It will be obvious that certain parts of the system herein described can be used without others, and the details herein described may be modified, all without departing from the scope of the appended claims.

It will be understood that the invention herein described is not restricted to the ultimate control of an air brake or other train retarding means, but magnets such as 34, 38 can be used for controlling other devices. Specific claims are not herein made to the various individual novel elements and combinations herein disclosed as they are of wider utility and will be covered in one or more divisional applications.

Having thus described my invention, what I declare as new and desire to secure by Letters Patent of the United States is:—

1. In a railway system, means for detecting on a train the condition of the track ahead including external sources of currents of different predetermined frequencies each controlled by a different track condition, and a plurality of devices on the train each constructed to respond to one of said currents.

2. In a railway system, means for detecting on a train the condition of the track ahead including external sources of currents of different predetermined frequencies, track circuits for controlling said currents each in accordance with a different track condition, a plurality of devices on the train in a circuit connected to said sources each responsive to a different current frequency, and a separate magnet controlled by each frequency responsive device.

3. In a railway system, a wayside primary circuit including a direct current E. M. F. connected across the rails, means for continuously interrupting said circuit to produce a current of predetermined frequency when a predetermined condition exists, and an inductively related secondary circuit on

the train including a device tuned to be responsive to induced current of such predetermined frequency.

4. In a railway system, a primary circuit including a direct current E. M. F. connected across the rails, a plurality of selectively controlled wayside means for continuously interrupting said circuit to produce currents of different predetermined frequencies when different conditions exist, and an inductively related secondary circuit on a train including a plurality of devices differently tuned to be only responsive to one of said currents of predetermined frequency.

5. The combination with a rail comprising correlated blocks, of means whereby certain conditions in said blocks will produce a pulsating current of predetermined tuned frequency across the rails in one of said blocks, a secondary train carried circuit in inductive relation to the circuit containing said current of tuned frequency, and a device in said secondary circuit tuned to be responsive to current of the predetermined tuned frequency.

6. The combination with a rail divided into blocks, of a relay in each block responsive to the presence of a train therein, a switch controlled by one relay, a magnet in an adjoining block responsive when said switch is actuated, said magnet being connected with the winding of the relay in said adjoining block, means for applying a periodic current to said latter block upon predetermined operation of said relays, and controlling means responsive to said periodic current.

7. The combination with a rail comprising two blocks, of a track circuit and train responsive relay for each block, a magnet coil in circuit with the winding of one relay and the armature of the other, a vibratory armature therefor, means causing said armature to vibrate when both relays are deenergized, and a device responsive to vibration of said armature.

8. The combination with a rail comprising two blocks, of a track circuit and train responsive relay for each block, a magnet coil in circuit with the winding of one relay and the armature of the other, an armature therefor, means causing said coil to move said armature when both relays are deenergized, a device in one block responsive when said armature is moved, said armature periodically interrupting the energizing circuit of said device.

9. The combination with a rail comprising two blocks, of a track circuit and train responsive relay for each block, a magnet coil in circuit with the winding of one relay and the armature of the other, an interrupter controlled by said coil to periodically interrupt the energizing circuit thereof, and

a device responsive to said interrupted current.

10. The combination with a rail comprising two blocks, of a track circuit and train responsive relay for each block, a magnet coil in circuit with the winding of one relay and the armature of the other, a device in one block responsive upon predetermined magnetization of said coil to periodically interrupt the energizing circuit thereof, a circuit for said interrupted current across said rails and carried by a train, a second circuit on the train in inductive relation to said first circuit, and a device on the train responsive to current induced in said second circuit.

11. The combination with a rail comprising two blocks, of a track circuit and train responsive relay for each block, and a controlling means in one of said blocks operative when said track relays are both in train responsive position, said means including a normally balanced magnetic circuit, and a device controlled by unbalancing thereof.

12. The combination with a rail comprising two blocks, of a track circuit and train responsive relay for each block, and controlling means in one of said blocks operative when said track relays are both in train responsive position, said means including a normally balanced magnetic circuit, means for unbalancing said circuit when a train is in one block without affecting said device, means for actuating said device when a train enters the other block, and a signal controlled thereby.

13. The combination with a rail comprising two blocks, of a track circuit and train responsive relay for each block, and controlling means in one of said blocks operative when said track relays are both in train responsive position, said means including a normally balanced magnetic circuit, means for unbalancing said circuit when a train enters one block, means effective upon predetermined additional unbalancing for applying a periodic current across the block containing said train, and a device controlled by said first named means.

14. The combination with a rail comprising two blocks, of a track circuit and train responsive relay for each block, controlling means in one of said blocks operative when said track relays are both in train responsive position, said means including normally balanced magnetic circuits which are unbalanced upon opening of one thereof, means for opening one circuit, means effective upon such opening for applying a periodic current across the block connected with said circuit, and a magnet controlled by said first named means.

15. In a railway control system, a plurality of devices in a block each producing

across the rails a different periodic current corresponding to a different traffic condition, train carried devices each responsive to one of said periodic currents, and means controlled thereby to indicate a particular condition.

16. In combination with a primary circuit in part on a train, a secondary circuit in inductive relation therewith, a device responsive only to induced current in said secondary circuit, a source of periodic current for said primary circuit, a source of current connected in said secondary circuit, and an indicating device responsive both to current from said latter source and to operation of said induced current responsive device.

17. The combination with a rail comprising two blocks, of a track circuit and train responsive relay for each block, and controlling means in one of said blocks operative when said track relays are both in train responsive position, said means comprising means for applying a periodic current across the rails, a circuit on the train in inductive relation to the circuit carrying said periodic current, and a device on the train responsive only to current of a predetermined frequency in said circuit.

18. In a railway block system, a plurality of means for producing across the rails thereof periodic currents of respectively different frequencies, train carried devices responsive respectively to said different periodic currents, and controlling means operated by either of said currents in a manner varying according to the particular current applied to it by the effective train carried device.

19. The combination with a rail comprising two blocks, of a track circuit and train responsive relay for each block, controlling means in one of said blocks operative when said track relays are both in train responsive position for applying a periodic current across the rails, a circuit on the train responsive thereto, a control device operated by said circuit, and means for rendering the train circuit self detecting.

20. In combination with a track circuit and means for applying a periodic current across the rails and through the wheels and axle of a train, a magnetic core surrounding the axle, a secondary wound on said core, a vibrator in said secondary responsive to current induced therein, an indicator controlled thereby, and a source of auxiliary current connected to said secondary circuit and having its circuit normally closed through said indicator, whereby the latter is responsive either to induced current in said secondary or to an open circuit therein.

21. The combination with a rail comprising two blocks, at least one of said blocks being sectioned, of a track circuit and train responsive relay for each block, and control-

ling means in one of said blocks operative when said track relays are both in train responsive position, said sectioned block having means for relaying the control between the sections thereof.

79

22. The combination with a rail comprising two blocks, at least one of said blocks being sectioned, of a track circuit and train responsive relay for each block, and controlling means in one of said blocks operative when said track relays are both in train responsive position, said sectioned block having means for relaying the control between the sections thereof without affecting the normal transmission of signal energy.

80

22. In a train control system, a primary circuit including a track battery, an interrupter, the track rails, train wheels and a wheel axle, a secondary circuit in inductive relation to said axle, and a device on the train tuned to be responsive to current of like frequency induced in said secondary circuit.

24. In a train control system, a primary circuit including a track battery, an interrupter, the track rails, train wheels and a wheel axle, a magnetic core surrounding said axle and having an air gap, said secondary circuit being wound on said core, and a device on the train tuned to be responsive to current of like frequency induced in said secondary circuit.

90

25. In a train control system, a primary circuit including the track rails, train wheels and a wheel axle having its surface provided with a conductor of different material having higher conductivity and electrically connected to the wheels.

100

26. A railway train control system embodying a track section, means selectively controlled by different conditions in said track section for producing a pulsating current of a different frequency for each track condition, and means differentially responsive to each frequency for indicating at a distant point the several different track conditions.

110

27. In a train control system, the combination with a periodic primary circuit controlled by track conditions, of means predeterminedly the periodicity of said current, a secondary train carried circuit, and a plurality of reeds each responsive to respectively different frequencies of secondary current, and a different indicating device, controlled by each reed.

115

28. In a railway system, a track relay across the rails, a battery across the rails for energizing said relay, a vibrator in said battery circuit, means for actuating said vibrator to intermittently open said battery circuit at the vibrator to periodically interrupt the current across the rails, and a device responsive to periodic current.

125

29. In a train control system, a primary

130

circuit including a source of periodic current, an inductively related secondary circuit containing a magnetic relay winding and a local battery on normally closed circuit, a vibratory reed controlled by induced current through said magnetic relay winding, and a control magnet having its circuit controlled by said vibratory reed.

30. In a railway system, a source of direct current E. M. F. adapted to be connected across the rails, a plurality of vibrators for interrupting said E. M. F. to produce currents of different predetermined frequen-

cies, means controlling said vibrators in accordance with traffic conditions so that one 15 is effective at a time, train carried devices each responsive to one of said frequencies, and an indicator controlled by each frequency responsive device.

In testimony whereof I affix my signature, 20 in presence of two witnesses.

MAXIMILIAN WEIL.
